(57) **CLAIM**

The ornamental design for a harness for upper extremity below-elbow prosthesis, as shown and described.

DESCRIPTION

FIG. 1 shows a perspective view of a harness for an upper extremity below-elbow prosthesis;

FIG. 2 shows a front view of the harness for upper extremity below-elbow prosthesis;

FIG. 3 shows a rear view of the harness for upper extremity below-elbow prosthesis;

FIG. 4 shows a right side view of the harness for upper extremity below-elbow prosthesis;

FIG. 5 shows a left side view of the harness for upper extremity below-elbow prosthesis;

FIG. 6 shows a top plan view of the harness for upper extremity below-elbow prosthesis; and,

FIG. 7 shows a bottom plan view of the harness for upper extremity below-elbow prosthesis.

The shade lines in the Figures show contour and not surface ornamentation.

The broken lines shown in the Figures show portions of the harness for upper extremity below-elbow prosthesis device which form no part of the claimed design.
